UNITED STATES PATENT OFFICE.

SIDNEY A. REEVE, OF WORCESTER, MASSACHUSETTS, ASSIGNOR TO CHARLES F. BROWN,
TRUSTEE, OF READING, MASSACHUSETTS.

MEAN-PRESSURE APPARATUS.

No. 862,348.

Specification of Letters Patent.

Patented Aug. 6, 1907.

Application filed October 31, 1905. Serial No. 285,330.

To all whom it may concern:

Be it known that I, SIDNEY A. REEVE, a citizen of the United States, residing at Worcester, in the county of Worcester and State of Massachusetts, have invented 5 certain new and useful Improvements in Mean-Pressure Apparatus, of which the following specification and accompanying drawings illustrate the invention in a form which I now regard as the best out of the various forms in which it may be embodied.

10 This invention relates to apparatus for establishing and registering a mean gaseous pressure between two points or periods of different pressures, and to the application of such means in securing automatic regulation, as of the mean water-level in a continuous-flame internal-combustion generator for the purpose of obtaining uniform superheat. This purpose is illustrated in the case of a generator employing a-burner for compressed air and fuel, the products of combustion from which pass downwardly through a combustion-tube into a 15 body of water in a water-pot and emerge into the water through a series of perforations in the lower end of the tube. To obtain some degree of superheat in the steam generated by the passage of the hot gases, the water is so regulated in quantity that some of the upper holes in 20 the lower end of the combustion-tube will be uncovered or only slightly covered, and the depth to which they are immersed depends upon the degree in which the water-level within the tube is depressed by the flow of gases, and its level outside of the tube raised. It is 25 found that if an automatic regulator, for example, be applied to the generator and controlled by the water-level outside of the tube, so as to maintain this outside level constant, the superheat will vary, for upon an increase in the pressure of the gases within the combustion-tube, a greater quantity of these products of combustion will pass unquenched through the upper holes and vice versa, while on the other hand if the inside level is maintained constant the superheat will also 30 vary, but in the opposite-way. In the ordinary operation of such a generator there is no actual mean level of water within and without the combustion-tube, merely a theoretical mean, but I have invented a means of obtaining a body of water at a mean level between these two levels and have devised a way of regulating the 35 water-supply so that this mean level is maintained substantially constant and the superheat accordingly rendered uniform under different pressures and volumes of gaseous flow. This means includes a device for obtaining a mean pressure between the gaseous pressures 40 anterior and posterior to the water-body which I also claim as a new invention. In a preferred form the latter device embodies a loop conduit connecting the space anterior to the water body with the space posterior

thereto so that the gaseous flow may by-pass around the water-body without being subjected to the resistance of the latter. Restricted passages at two points in said conduit include between them a mean-pressure chamber in which, owing to the high frictional resistance imposed upon the flow by these passages, the pressure will be a mean or average between the combustion-chamber pressure and the lower cooling-chamber pressure. If now, a U-tube have one of its ends connected with this mean-pressure chamber and the other end connected with the water-pot, the water in the outer leg of said U-tube will stand at a level intermediate between the levels inside and outside the combustion-tube and may be registered by a gage-glass. This mean level of water may then be kept constant by hand-regulation of feed or by automatic regulation, all as more particularly described hereinafter.

70 Of the accompanying drawings, Figure 1 represents a diagrammatic view partly in section, showing an apparatus constructed according to my invention and including a constant-pressure internal-combustion generator together with the mean-pressure, mean-level and automatic mean-level-controlling devices which constitute the invention, the engine and compressors forming a part of the complete apparatus being shown on a smaller scale. Fig. 2 represents an enlarged section of one of the resistances and its adjusting valve.

80 The same reference-characters indicate the same parts in both figures.

Referring to the drawings, 10 indicates the generator, comprising principally an outer casing 11 whose lower part 12 constitutes the water-pot or cooling-chamber, 85 a burner 13 for the compressed air and gas coming through pipes 14, 15 from compressors 16, 17 driven by an engine 18, an automatic regulating valve-mechanism 19 for the air and gas going to the burner, and a combustion-tube 20 opening into the water-pot and 90 having a series of perforations 21 in its lower portion, distributed between different levels, through which the products of combustion pass out into the cooling-chamber. The tube and water-pot thus form a return-bend in the pressure-line. The mixture of steam 95 and gases passes upwardly around the outside of the combustion-tube 20 through the upper space or channel 22 and out through the pipe 23 to drive the engine 18. If one or more of the uppermost rows of holes 21 is uncovered by water on the outer side of the tube 20, 100 some products of combustion will by-pass unquenched around the water-body and serve to superheat the steam with which they mingle in passing upwardly.

105 24 is a pipe connected with a pump, for supplying feed-water to the water-pot 12.

25 indicates a loop or by-pass conduit connected at

one end with the upper space 22 forming the outlet passage of the cooling-chamber and at its other end with the interior of the combustion chamber or with some point in the pressure-line having an equivalent pressure. In the drawing two alternative connections are shown. One is a short pipe 26 having stop-valve 27 and connected with the combustion-tube interior above the level which the inner end of the water-body assumes under running conditions but below 10 the outer water-level, so that the hot products of combustion may be somewhat cooled in passing through the loop. The other pipe connection 28, containing stop-valve 29, leads from an ante-chamber 30, which may be traversed by a flow of secondary air and contains substantially the same pressure as the combustion-chamber. These pipes may be of any desired 15 length or shape to effectually cool the flow through them by traversing the passage 22 and to provide for unequal expansion. When the pipe 28 contains a flow of secondary air only, it does not need cooling. Either avenue 26 or 27 may be used or both may operate at 20 the same time.

In the conduit 25 are located two restricted passages 31 controlled by adjustable needle-valves 32 so as to 25 offer a high resistance to the gaseous flow as compared with the resistance offered by the body of the loop 25. That portion 33 of the conduit which is located between the resistances 31 constitutes the mean-pressure chamber. To it is connected the upper end of a registering loop 34, 35, 36 and a parallel loop 37, 38, 39, whose lower ends are connected with the water-pot 12. The leg or water-column 35 is a gage-glass for giving a visual indication of the mean water-level X—X and the portion 38 is part of an automatic diaphragm feed-regulator 40 operating a by-pass feed-valve 41. This particular regulator operates by a differential pressure on opposite sides of its diaphragm caused by the covering or uncovering of an inlet 42 to its upper diaphragm-chamber, located at the intended constant water-line. Any other suitable form of automatic feed-controller may however be employed to maintain a substantially constant level in the water-legs 35 and 38. Automatic control could of course be dispensed with if desired.

45 In operation, by a suitable adjustment of the resistances 31, the pressure in chamber 33 may be made a close arithmetic mean or average between the pressure within the combustion-chamber on one side of the water-body and the pressure in the space 22 on the opposite side. The water-columns in the legs 35 and 38 will register the corresponding mean water-level, because the pressure on the inner leg of the U-tube formed by the water-pot and these legs will be a resultant or mean between the pressure acting downwardly on the water-body in the combustion-tube 20 and the pressure acting downwardly thereon in the space 22, while the pressure in the other double leg 35 38 is that mean between these two pressures which exists in the chamber 33. The controller 40 so regulates the supply of feed-water to the water-pot 12 that this mean level in legs 35 38 is maintained substantially constant. Accordingly the two levels within the water-pot may depart or approach to accommodate the volume of products of combustion 60 65 which may be flowing at any one time and the super-

heat caused by the passage of unquenched gases through the upper rows of perforations 21 will remain substantially constant in degree. For the perfection of this result, the cross-sectional areas of the spaces inside and outside of the combustion-tube might be 70 made substantially equal so that the depression of water-level on one side will equal the rise on the other side.

What I claim as new and desire to secure by Letters Patent is:

1. The combination of a plurality of chambers, means to establish different gaseous pressures therein, and a conduit connecting them and having resistances between which is established a pressure-mean between the two chamber pressures. 75
2. The combination of means for establishing two different elastic fluid pressures, a conduit subject at its ends to the respective pressures, resistances in said conduit, and a mean-pressure chamber in said conduit between the resistances. 80
3. The combination of means for establishing two different elastic-fluid pressures, a conduit subject at its ends to the respective pressures, resistances in said conduit, a mean-pressure chamber in said conduit between the resistances, and means for separately adjusting the resistances. 85 90
4. The combination of a gaseous-pressure line adapted to sustain a continuous flow, means whereby the pressures at different points in said line are maintained at different intensities, a loop-conduit connecting said points of different pressures and containing a mean-pressure chamber, and resistances in said conduit at both ends of said chamber. 95
5. The combination of a gaseous-pressure line having a return-bend, means to maintain in said bend a body of water whose ends are established at different levels by the gaseous flow, means for establishing a pressure-mean between the pressures on the two ends of the water body, and a tube for registering the corresponding mean water-level, said tube having one end connected with the return-bend, and the other end subject to the mean gaseous pressure. 100
6. The combination of a gaseous-pressure line including an internal-combustion burner, means for maintaining a body of water affording resistance in the path of the products of combustion from said burner, a loop conduit connecting points in said pressure-line anterior and posterior to the water-body and containing a mean-pressure chamber, and resistances in said conduit at the entrance and exit of said chamber. 105
7. The combination of an internal-combustion generator having a water-pot adapted to contain a body of water, a combustion-chamber discharging thereinto, a mean-pressure chamber receiving the combustion-chamber flow anterior to the water-body and discharging into the outlet from said pot, and resistances at the entrance and exit of said mean-pressure chamber. 110
8. An internal-combustion generator comprising a combustion-tube and water-pot forming a return bend, said tube having a total outlet distributed between different levels, a chamber receiving the mean pressure between points anterior and posterior to said return-bend, and a registering tube connected at one end with said chamber 115 120 and at the other end with the water-pot. 125
9. The combination of a water-pot, a combustion-tube having a plurality of outlets at different heights therein, a chamber receiving the pressure-mean between points anterior and posterior to said outlets, and a visual water-column connected at one end with said chamber and at the other end with said water-pot. 130
10. The combination of an internal-combustion vaporizing and superheating generator comprising a combustion-chamber, a vaporizing chamber adapted to contain a body of water whose mean level determines the degree of superheat in the motive mixture supplied by the generator, a chamber receiving the pressures anterior and posterior to the vaporizing chamber and having inlet and outlet resistances, and a registering column connected at opposite ends with said vaporizing chamber and the outlet thereof respectively. 135
11. The combination of a water-pot, a combustion-cham-

ber discharging thereinto, a water-column connected at one end with the water-pot and receiving at the other end the pressure-mean between points anterior and posterior to the water-pot, and means controlled by the water-level in said 5 column for maintaining said level substantially constant.

12. The combination of an internal-combustion burner, means for maintaining a body of water in the path of the products of combustion, means whereby the anterior and posterior surface-levels of said water-body are caused to differ by different amounts corresponding to the volume of 10 gaseous flow from said burner, means for registering the mean water-level of said body, and mechanism subject to said mean level for automatically maintaining the same substantially constant.

15. 13. In combination, a generator having a water-pot, a combustion-tube having a plurality of outlets therein at different heights, a loop-conduit connecting pressure-points anterior and posterior to said water-pot, adjustable resistances in said conduit, a registering loop connected at its 20 lower end with the water-pot and at its upper end with

said loop-conduit between the resistances in the latter, means for supplying feed-water to said water-pot, and an automatic controller governing the supply of feed-water and controlled by the water-level in the registering loop.

14. In combination a generator having a continuously- 25 operative burner and combustion-tube, a water-pot for quenching the products of combustion, means to supply air and fuel under pressure to said burner, and a by-pass leading from a point in the air-line anterior to the burner to a point in the pressure-line posterior to the water-pot and 30 containing obstructions adapted to form a mean-pressure chamber in the by-pass.

In testimony whereof I have hereunto set my hand in the presence of two subscribing witnesses, the 27th day of October 1905.
